UNITED STATES PATENT OFFICE.

GEORGE H. WHITTINGHAM, OF BALTIMORE, MARYLAND, ASSIGNOR TO MONITOR
CONTROLLER COMPANY, OF BALTIMORE, MARYLAND, A CORPORATION OF MARY-
LAND.

RESISTOR.

Application filed December 27, 1926. Serial No. 157,168.

The invention relates to a core for resistors used on high tension circuits. The core of the resistor is made of porcelain. As this material cannot be made in long pieces without warping, it has heretofore been made in relatively short sections and affixed upon a metal supporting bar. It is desirable, where the resistor is used on high tension circuits, to omit the metal supporting bar, and the purpose of the present invention is to provide a core for the resistor composed of a plurality of relatively short sections of porcelain, so interlocked with one another that when the helix is wound upon the core the latter will be a rigid structure without a bar for supporting the sections.

In my Patent No. 1,648,871, dated Nov. 8, 1927, I have shown and described a resistor comprising a metal supporting bar and a covering of insulating material thereon, comprising a plurality of relatively short sections, each having a beveled end abutting against a like end of another section, so that the convolutions of the helix of resistance wire, wound on the covering, will cross the joints between the sections at an angle, and there are no crevices into which the convolutions of the helix may slip. In the present invention, the short sections of insulating material are of the same design as the sections shown in the aforesaid application, with additional features by which the various sections become interlocked against endwise or lateral movement, so that when the parts are held together by the resistance wire wound upon the core, the latter will form a rigid structure which does not require a bar to support its various sections.

In the accompanying drawing, which illustrates the invention,

Fig. 1 is a plan view of a resistor made according to my invention, the core being partly broken away, and only parts of the helix being shown;

Fig. 2 is a similar view of a core, showing the same assembled upon a temporary supporting bar;

Fig. 3 is a plan view showing the outer surface of one-half of the core;

Fig. 4 is a similar view showing the inner face of the other half of the core;

Fig. 5 is a perspective view of one of the end sections of the core;

Fig. 6 is a similar view of one of the central sections;

Fig. 7 is a section on the line 7—7 of Fig. 2;

Fig. 8 is a section on the line 8—8 of Fig. 2; and,

Fig. 9 is a section on the line 9—9 of Fig. 1.

Referring to the drawing, the core A of the resistor is composed of a plurality of semi-cylindrical sections of refractory insulating material, porcelain, one of the end sections a being shown in perspective in Fig. 5, and one of the intermediate sections b being similarly shown in Fig. 6. Each end section has a narrow groove 1, extending centrally along its inner face, from end to end of the section, and it also has two parallel grooves 2 and 3, at opposite sides of the groove 1, the grooves 2 and 3 preferably being semi-circular in cross section. In these latter grooves are integral stops or shoulders 4 and 5, respectively, which project above the inner face of the section and are adapted to fit within like grooves in other sections. One end of each end section is at right angles to the body of the section and is preferably formed with a flange 6, and the other end of the section is beveled or inclined, as shown at 7 in Fig. 5. Each intermediate section, as shown in Fig. 6, has both ends 8 and 9 beveled or inclined at the same angle as the beveled ends of the end sections. Each intermediate section also has a central groove 1^a and grooves 2^a and 3^a, corresponding to the grooves 1, 2 and 3 in the end sections. Each intermediate section also has integral stops 10 and 11 in the groove 2^a and stops 12 and 13 in the groove 3^a, these stops projecting above the faces of the sections and adapted to enter like grooves in opposing sections.

The assembled core comprises the end sections and a sufficient number of intermediate sections to make the core of the desired length. In the drawing, for the purpose of illustration, the core is shown composed of the end sections and one pair of intermediate sections. In building up the core, the sections

are temporarily assembled upon a flat metal bar 14, Figs. 2 and 8, and this bar is afterwards withdrawn. A series of sections, as a' , a^2 and a^3 , Fig. 4, is assembled on one edge 5 of the bar, this bar entering the central grooves 1, 1^a . An opposing series of sections, Fig. 3, is then assembled on the opposite edge of the bar, and the sections in the two series, meeting face to face, form a cylinder, as illustrated in Fig. 8.

Fig. 4 shows end sections a' and a^2 and one intermediate section b' , arranged end to end; and Fig. 3 shows an opposing series of sections, a^3 , b^2 and a^4 , adapted to be assembled 15 on the bar over the series shown in Fig. 4. In Fig. 3, which shows the outer sides of the sections, the stops or shoulders on the sections are shown in dotted lines.

When the series of sections shown in Fig. 20 3 is assembled upon the bar 14, opposite the series shown in Fig. 4, the stops or shoulders on the several sections will be in the relation indicated in Fig. 2. The stops 10 and 12 on the section b' are staggered and the corresponding staggered stops 10 a and 12 a will fit 25 against opposite sides of the stops 10 and 12. This engagement of the stops will prevent relative endwise movement of the opposed intermediate sections. The stop 11 on the intermediate section 3 a will engage the rear end of the stop 5 a on the end section a^2 and thus prevent endwise movement of the latter section, and the stop 11 a on the intermediate section b^2 will be located back of the 30 stop 5 on the opposed end section a' . Thus, both of the end sections a' and a^3 will be interlocked with the intermediate sections so that the sections cannot be pulled apart. The stop 5 on the end section a^2 will stand back of the stop 13 a on the overlapping portion of the intermediate section b^2 , and the stop 13 on the intermediate section b' will extend back of the stop 5 a on the opposed end section a^4 . Thus, the ends sections a^2 and a^4 will also be 45 interlocked with the intermediate sections to prevent relative endwise movement between these sections. The stops 4 and 4 a in the end sections do not interlock with intermediate sections, but these stops, together with all of the other stops or shoulders, serve to hold the 50 upper series of sections against lateral movement with respect to the lower series when the bar 14 is removed from the core.

After the sections have been assembled in 55 the manner described, upon the metal bar, the wire helix c is wound upon the core. Prior to the winding of the helix, the sections may be held together by removable clamps and as the wire is wound upon the core these clamps 60 may be removed. It will be evident that the winding of the wire upon the core will hold the sections tightly together so that they cannot move apart radially, and as they are interlocked by the shoulders against relative 65 longitudinal and lateral movement, the

finished resistor will be a rigid structure even after the metal bar is withdrawn from the core.

Thus, a resistor of any desired length may be built up, having a core made entirely of 70 porcelain. The resistor may be supported out of contact with metal parts by insulators d , mounted upon a suitable frame and having prongs 15 which enter the grooves 2 and 3 in the end sections and abut against the stops or 75 shoulders 4 and 4 a , as illustrated in Fig. 1. The convolutions of the helix cross the joints between the sections at an angle and therefore these convolutions cannot slip into any crevices between the sections. The terminals e 80 may be held upon the core by winding a few turns of the wire over the flanged bases of the terminals, as further explained and illustrated in my co-pending application previously referred to.

What I claim is:

1. A resistor comprising a core and a wire coil wound thereon, said core comprising two parallel opposing series of relatively short sections of refractory material, held against 90 one another by said coil, sections in one series overlapping sections in the other series and interlocking therewith to prevent relative endwise movement of the sections in one series 95 with respect to the sections in the other series.

2. A resistor comprising a core and a wire coil wound thereon, said core comprising two parallel opposing series of relatively short sections of refractory material, held against 100 one another by said coil, sections in one series overlapping sections in the other series and interlocking therewith to prevent relative endwise and lateral movement of the sections in one series with respect to the sections in 105 the other series.

3. A resistor comprising a core and a wire coil wound thereon, said core comprising two parallel opposing series of relatively short sections of refractory material, held against 110 one another by said coil, the sections in each series arranged end to end and each section in one series overlapping the end portion of a section in the opposing series, said overlapping 115 portions having parts which interlock and prevent relative endwise movement between the sections.

4. A resistor comprising a core and a wire coil wound thereon, said core comprising two parallel opposing series of relatively short sections of refractory material, held against 120 one another by said coil, the sections in each series arranged end to end and each section in one series overlapping the end portion of a section in the opposing series, said overlapping 125 portions having parts which interlock and prevent relative endwise and lateral movement between the sections.

5. A resistor comprising a core and a wire coil wound thereon, said core comprising two 130

- parallel opposing series of relatively short sections of refractory material, held against one another by said coil, the sections in each series having beveled abutting ends and each 5 section in one series overlapping the end portion of a section in the opposing series, said overlapping portions having parts which interlock and prevent relative endwise movement between the sections. 70
- 10 6. A resistor comprising a core and a wire coil wound thereon, said core comprising two parallel opposing series of relatively short sections of refractory material, held against one another by said coil, the sections in each 15 series having beveled abutting ends and each section in one series overlapping the end portion of a section in the opposing series, said overlapping portions having parts which interlock and prevent relative endwise and lateral movement between the sections. 75
- 15 7. A resistor comprising a core and a wire coil wound thereon, said core comprising two parallel opposing series of relatively short sections of refractory material, held against one another by said coil, each series comprising 20 end sections and an intermediate section, the sections in each series arranged end to end and each section in one series overlapping the end portion of a section in an opposing section, the opposed intermediate sections having 25 parts which interlock to prevent relative endwise movement of said intermediate sections, and the overlapping portions of the sections in one series having parts which interlock with the overlapping portions of the sections of the opposing series and prevent 30 relative endwise movement between the sections of both series. 80
- 20 8. A resistor comprising a core and a wire coil wound thereon, said core comprising two parallel opposing series of relatively short sections of refractory material, held against one another by said coil, each section being 35 hemispherical in cross section and having spaced longitudinal grooves on its inner side, the sections in one series overlapping sections 40 in the opposing series, and each section having a shoulder in one of its grooves interlocking with a shoulder in a groove in the overlapping portion of an opposing section. 85
- 25 9. A resistor comprising a core and a wire coil wound thereon, said core comprising two parallel opposing series of relatively short sections of refractory material, held against one another by said coil, each section being 45 hemispherical in cross section and having spaced longitudinal grooves on its inner side, the sections in one series overlapping sections 50 in the opposing series, each section having a shoulder in one of its grooves interlocking with a shoulder in a groove in the overlapping portion of an opposing section. 90
- 30 10. A resistor comprising a core and a wire coil wound thereon, said core comprising two 55 parallel opposing series of relatively short sections of refractory material, held against one another by said coil, each section being hemispherical in cross section and having spaced longitudinal grooves on its inner side, the sections in one series overlapping sections 60 in the opposing series, each section having a stop in one of its grooves projecting above the inner face of the section and extending within the groove in an opposing section. 95
- 35 11. A resistor comprising a core and a wire coil wound thereon, said core comprising two 65 parallel opposing series of relatively short sections of refractory material, held against one another by said coil, each section being hemispherical in cross section and having spaced longitudinal grooves on its inner side, the sections in one series overlapping sections 70 in the opposing series, and each section having a stop in one of its grooves projecting above the inner face of the section and interlocking with a stop in the overlapping portion of an opposing section. 75
